UNITED STATES PATENT OFFICE.

WILLARD C. LIPE, OF SYRACUSE, NEW YORK.

BROOM-SEWING MACHINE.

SPECIFICATION forming part of Letters Patent No. 718,263, dated January 13, 1903.

Application filed May 10, 1902. Serial No. 106,831. (No model.)

To all whom it may concern:

Be it known that I, WILLARD C. LIPE, of Syracuse, in the county of Onondaga and State of New York, have invented a certain 5 new and useful Sewing-Machine, of which the following is a specification.

This invention relates to a broom-sewing machine, and has for its object the production of a machine which is especially practical and simple in construction and highly effective and durable in use; and to this end it consists in the novel combinations and constructions hereinafter described, and pointed out in the claims.

15 In describing this invention reference is had to the accompanying drawings, in which like letters indicate corresponding parts in all the views.

Figure 1 is a perspective view of a preferred 20 construction of my machine, an unsewed broom being arranged therein. Fig. 2 is a side elevation, partly in section, of the greater portion of the machine shown in Fig. 1. Fig. 3 is a top plan of my machine, the greater 25 portion of the sewing mechanism being removed for illustrating the vise and its feeding mechanism. Fig. 4 is a front elevation of the detached vise and parts supported thereby. Fig. 5 is a side elevation of the upper portion of the parts seen in Fig. 4, a broom being shown as engaged by the vise. Fig. 6 is a sectional view taken on line 6 6, Fig. 4. Figs. 7 and 8 are respectively a face view, partly in section, and an end elevation of 30 the engaging part secured to one of the outer jaws of the vise and cooperating with means secured to the other outer jaw of the vise for moving one of these jaws toward and away from the other. Figs. 9 and 10 are views of a connection between the needle carried by 35 the vise and the broom-support. Fig. 11 is a vertical sectional view taken on line 11 11, Fig. 5. Fig. 12 is a top plan of part of the detached support for the broom. Fig. 13 is a vertical sectional view of a guide for the handle of the 40 broom. Fig. 14 is a detail view of a portion of one of the jaws of the vise and a movable part secured thereto for determining the starting position of the vise. Fig. 15 is a side elevation of a portion of one of the jaws of the 45 50

vise and contiguous parts for controlling the downward movement of the broom-support and for raising said support to its initial position. Figs. 16 and 17 are front elevations, partly in section, of the means shown in Fig. 55 15. Figs. 18, 19, and 20 are detail views of part of the rack controlling the movement of the broom-support, portions of the pawls coöperating with said rack, and the cams for forcing the pawls from their operative position. 60 Fig. 21 is a detached view of said cams, parts of the manually-operated member provided with the cams, and a portion of the means for elevating the broom-support. Fig. 22 is a sectional view taken on line 22 22, Fig. 21. 65 Figs. 23, 24, and 25 are sectional views taken, respectively, on lines 23 23, Fig. 3, 24 24, Fig. 23, and 25 25, Fig. 24. Fig. 26 is a plan of a portion of the connections between the vise and its feeding means. Fig. 27 is a sectional 70 view taken on line 27 27, Fig. 26. Fig. 28 is a front elevation of the driving-pulley and contiguous parts of the machine. Fig. 29 is a vertical sectional view of the upper portion of the parts shown in Fig. 28. Fig. 30 is an 75 elevation of the driving-pulley and part of the means for locking said pulley to its shaft. Fig. 31 is a sectional view of the detached friction-band for engaging the driving-pulley, taken on line 31 31, Fig. 30. Figs. 32, 33, and 80 34 are respectively a top plan and side and front elevations, partly broken away, of the greater portion of the detached sewing mechanism of this machine, a part of the main frame being indicated in Fig. 34. Fig. 35 is 85 a front elevation, partly broken away, of the parts illustrated in Fig. 34, the needles being shown in their intermediate positions. Figs. 36 and 37 are views of a needle and contiguous parts of the means for supporting and 90 moving the needle. Figs. 38 and 39 are sectional views taken, respectively, on line 38 38, Fig. 37, and 39 39, Fig. 38. Fig. 40 is an elevation of the removable part of the holder for the needle. Figs. 41 and 42 are elevations of 95 one of the loopers and its actuating means. Fig. 43 is a sectional view taken on line 43 43, Fig. 42. Fig. 44 is a view of a portion of one of the looper-sections. Fig. 45 is an elevation of the band-lifter and contiguous parts. 100

The illustrated preferred embodiment of this machine comprises a main frame A, a vise B, and feeding and sewing mechanisms.

As is obvious, the frame A is of any desirable form, size, and construction.

The vise B, Figs. 1 to 22, inclusive, usually consists of opposing jaws b b' , a support b^2 for the broom B' , a manually-operated member b^3 , connected to said jaws and support, a movable part b^4 for determining the starting position of the vise, and a guide b^5 for the handle of the broom. Said jaw b is shown as secured at its intermediate portion to the frame A by a pivot a , upon which the jaw moves to and fro or in opposite directions from front to rear of the machine and toward and away from the needle-path. The jaw b is prevented from lateral movement by suitable means, Figs. 1 and 11, as separated bearing-surfaces b^6 b^{60} , arranged at opposite sides of the axis of said jaw and engaged with corresponding faces a' upon the frame A, and as the jaw b swings on its axis in either direction beyond an intermediate vertical position it is subjected to the action of means here illustrated, Fig. 2, as comprising separated stops a^2 , a connection c , and a spring c' . The stops a^2 generally consist of opposing shoulders on the frame A. The connection c is pivoted to the lower end of the jaw b , is movable with the vise B in opposite directions relatively to the stops a^2 , and is provided with normally fixed shoulders c^2 , which are movable through narrow slots a^3 , opening through the opposing surfaces of the stops or shoulders a^2 , and are usually arranged in two openings of a series of openings in the connection c , that permit adjustment of said shoulders c^2 toward and away from each other, and the spring c' is arranged on the connection c between the shoulders c^2 , and as the vise swings to and fro beyond its intermediate position opposite portions of the spring c' , as its ends, are alternately movable with the connection c and are alternately engaged with the stops a^2 and prevented from movement with the connection c , thus tensioning the spring, subjecting the vise to an increasing resistance when moving in either direction beyond its intermediate position, and storing energy in the spring, which tends to move the vise in opposite directions to said intermediate position. I preferably interpose washers c^3 between the shoulders c^2 and the ends of the spring c' ; but said washers may be dispensed with, if desired. Moreover, the shoulders c^2 may be dispensed with and the intermediate portion of the spring c' secured to the connection c ; but in such event only a part of the spring c' will be utilized to resist the movement of the vise in either direction and to assist in returning the vise to its intermediate position.

As best seen in Figs. 4 and 11, the jaw b' is movable laterally or relatively toward and away from the jaw b and is provided at its

lower end with an extension b^7 , projecting laterally beyond its broom-engaging face and secured by a pivot b^8 to said other jaw, at the outer side of the broom-engaging face thereof. The movement of the jaw b' from the jaw b may be limited by a screw a^4 , Fig. 1, normally fixed to the frame A. Said jaw b' is thus supported by the jaw b and movable with the same toward and away from the needle-paths, which extend upwardly toward the tops of said jaws, and when the jaw b' is moved on its pivot b^8 laterally or relatively toward and away from the jaw b the extension b^7 causes the upper edge of the jaw b' to move downwardly with minimum liability of the projection thereof into the upwardly-extending path of the corresponding needle.

The support b^2 is here shown as consisting of opposite sections or jaws having their opposing broom-engaging surfaces interposed between inner surfaces of the jaws b b' and preferably formed of suitable shape to give the desired form to the interposed part of the broom. This support b^2 is movable step by step relatively to the jaws b b' for arranging and holding the broom in the different positions which it assumes during the securement of a plurality of bands thereto. The opposite sections or jaws of the support b^2 are respectively guided in their downward movement by the jaws b b' , and one section or jaw of the part b^2 is supported by one of said jaws b b' , as the jaw b , and is connected to said jaw b by suitable means for preventing its lateral movement independently of the jaw b , and the other section or jaw of the part b^2 is supported by the section or jaw thereof supported by said one of the jaws b b' , as the jaw b , and is connected to the jaw b' by means which move the same laterally with said jaw b' . In the illustrated exemplification of this invention the desired support from one of the sections or jaws of the part b^2 to the other section or jaw thereof is afforded by arms b^9 , which project from the inner faces of the sections or jaws of the support b^2 , are substantially concentric with the pivot b^8 , engage transverse faces b^{10} , provided on said sections or jaws and formed concentric with said pivot, and are of such length that they are not moved out of engagement with the faces b^{10} when the jaws b b' are separated to permit the removal or insertion of the broom.

As seen in Fig. 11, the sections or jaws of the support b^2 are provided with downwardly-diverging faces b^{11} , which engage corresponding faces b^{12} of the jaws b b' . When the support b^2 is in its initial or elevated position and the broom is clamped in the vise, the jaws b b' press their engaging faces above the support b^2 firmly against said broom and also clamp the opposing surfaces of the sections or jaws of the support b^2 against the interposed part of said broom; but after the first band is secured to the broom and the support

*b*² has been depressed to its position assumed during the securement of the second band a lower and thinner portion of the broom is interposed between the engaging faces of the 5 jaws *b b'* above the support *b*², and the inclined faces *b*¹¹ *b*¹² permit said engaging faces of the jaws *b b'* to tightly clamp the thinner interposed part of said broom and prevent the jaws *b b'* from pressing the sections or 10 jaws of the support *b*² firmly against the broom, which is held in the desired form and against its expansion by the band previously secured thereto. It will therefore be understood that until the support *b*² has made its 15 first downward movement the faces *b*¹¹ *b*¹² co-operate to effect the firm clamping of the sections or jaws of the support *b*² upon the broom and that after the first downward movement of the support *b*² the faces *b*¹¹ *b*¹² prevent the 20 support *b*² from interfering with an effective clamping of said article by the jaws *b b'* and reduce the amount of labor necessary for securing the broom in the vise. As also seen in Fig. 11, each of the sections or jaws of the 25 support *b*² is composed of inner and outer divisions secured together by clamping-screws *b*¹³ *b*¹⁴, which are readily adjusted for permitting the detachment and securement of the support *b*² in position. The outer division 30 of the section or jaw of the support *b*², guided on the jaw *b*, is generally provided with a depending rack *b*¹⁴, and to permit adjustment of said rack relatively to the support *b*² the corresponding clamping-screw *b*¹³ is provided 35 with an eccentric sleeve *b*¹⁵, which encircles the part of this screw passed through said rack *b*¹⁴ and may be adjusted at will. The manually-operated member *b*³ is here shown as a shaft journaled in the jaw *b* and provided 40 with cams *b*¹⁶ *b*¹⁷ *b*¹⁸ and a handpiece *b*¹⁹. Said cam *b*¹⁶ is formed with an internal engaging face co-operating with an engaging part *b*²⁰, which, as here illustrated, is journaled in the jaw *b'*, is provided with an eccentrically-ar- 45 ranged peripheral face, Figs. 4, 8, and 11, for engaging with the cam *b*¹⁶, is adjustable relatively to said jaw *b'*, and is held in its adjusted position by a clamping-screw *b*²¹, Figs. 5 and 11. As the member *b*³ is rocked in re- 50 verse directions the cam *b*¹⁶ and the engaging part *b*²⁰ move the jaw *b'* laterally toward and away from the jaw *b* and lock the jaw *b'* in its adjusted position. The surface *b*²², Fig. 4, of the cam *b*¹⁶, which effects the final clamp- 55 ing of the broom by the jaws *b b'*, is preferably formed of such shape that the jaw *b'* is moved by the surface *b*²² toward the jaw *b* with increased power as said broom is finally compressed.

60 As best seen in Figs. 15 to 20, the cams *b*¹⁷ *b*¹⁸ co-operate with the pawls *d d'* of an escape- 65 ment for the rack *b*¹⁴ for permitting said rack and the support *b*² to move downwardly by gravity step by step at the time or after the jaw *b'* is moved from the jaw *b* and preventing the support *b*² from moving downwardly when the jaw *b'* is moved in the reverse di-

rection. The pawls *d d'* are forced to their operative position by springs *d*² *d*³, and the pawl *d'* is usually formed with a vertically- 70 elongated opening *d*⁴, Fig. 15, for receiving its pivot. When the broom is not within the vise *B*, the spring *d*³ raises the pawl *d'* as far as permitted by the elongated pivot-opening *d*⁴ and also slightly elevates the support *b*², 75 so that a small space intervenes between the lowest tooth of the rack *b*¹⁴ and the pawl *d*, as illustrated in Figs. 15 and 16; but when the support *b*² is subjected to the weight of the broom said support and the pawl *d'* are de- 80 pressed slightly against the action of the spring *d*³ until the engaging faces of both pawls *d d'* are in substantially the same horizontal plane and in contact with the lowest tooth of the rack *b*¹⁴, as seen in Fig. 18. 85

As the manually-operated member *b*³ is moved toward the right to clamp the jaws *b b'* upon a broom to which the first band is about to be sewed the cam *b*¹⁷ rocks the pawl *d* out of engagement with the rack *b*¹⁴; but 90 no downward movement of the rack takes place, as the pawl *d'* supports the rack in its elevated or initial position. During the continued movement of the member *b*³ toward the right the pawl *d* again engages the 95 lowest tooth of the rack *b*¹⁴, and immediately afterward the cam *b*¹⁸ rocks the pawl *d'* out of engagement with the rack *b*¹⁴, whereupon the pawl *d* prevents downward movement of the rack *b*¹⁴, and the pawl *d'*, owing to its 100 elongated pivot-opening, is moved upwardly by the spring *d*³, and when said pawl is again engaged with the rack *b*¹⁴ upon the passage of the cam *b*¹⁸ its engaging face is slightly above the lowest tooth of the rack *b*¹⁴, as indicated in Fig. 19. After the first band is secured to the broom the member *b*³ is rocked to the left to release said broom, and during this movement of the member *b*³ the cams *b*¹⁸ *b*¹⁷ successively actuate the pawls *d d'*; but 105 the support *b*² cannot move downwardly until the pawl *d* is forced out of its operative position, as indicated in Fig. 20, and the downward movement of the support *b*² is then limited by the pawl *d'*. Upon the return of 110 the member *b*³ to clamp the broom by the jaws *b b'* no dropping of the support *b*² takes place. The continued movements of the member *b*³ effect similar downward movements of the support *b*² whenever the pawls *d d'* are 115 actuated by the cams *b*¹⁸ *b*¹⁷ moving to the left.

In considering the operation of the pawls *d d'* it will be understood that when the member *b*³ moving to the right is about to cause the cam *b*¹⁸ to force the pawl *d'* from its operative position the broom is being clamped in position by the jaw *b'*, and its upper portion, which is partly compressed, tends to expand and produce sufficient friction between the vise and the broom to prevent the broom and 120 the support *b*² from moving downwardly slightly at the time the cam *b*¹⁸ moving to the right forces the pawl *d'* from its operative position and that for this reason I elongate the 125

pivot-opening of the pawl d' , so that said pawl may be moved by the spring d^3 slightly above the lower or other previously-engaged tooth of the rack b^{14} . If it were not for the tendency of the broom to expand and prevent a slight downward movement of the support when the cam b^{18} moving to the right forces the pawl d' from its operative position, the elongated pivot-opening of the pawl d' would be unnecessary and said pawl would have its engaging face normally arranged above the corresponding face of the pawl d . It will also be understood that when the operating member b^3 is moved to the left sufficiently to cause the cam b^{17} to actuate the pawl d the tendency of the broom to expand does not retard the dropping of the support b^2 , owing to the securing of one or more bands thereto and to the separation of the jaws b b' , effected by the cam b^{16} at the time the pawl d is actuated by the cam b^{17} .

It will be particularly noted that the operation of the member b^3 to both move the jaw b' toward and away from the jaw b and to actuate the pawls d d' is under the direct control of the operator and that he may move the member b^3 either to release the broom from the jaws b b' or to both release said broom and cause the same to move downwardly the desired step or distance.

In addition to actuating the jaw b' and the pawls d d' the manually-operated member b^3 also generally actuates suitable means which return the support b^2 to its elevated or initial position, and is here illustrated, Figs. 11, 15, 16, 17, 21, and 22, as consisting of a movable part or sleeve e and a link e' . The movable part or sleeve e is loosely mounted on a portion of the member b^3 and is provided with an engaging face e^2 in the path of a rigid arm b^{23} on said member and with an outwardly and upwardly projecting arm e^6 , connected by the link e' to the support b^2 . As the support b^2 moves downwardly the part or sleeve e moves loosely step by step on the member b^3 with the support b^2 , and when said support b^2 is in its depressed position the face e^2 of the part or sleeve e is in close proximity to the position of the arm b^{23} when the jaw b' is in its position of greatest separation from the jaw b . Consequently if the movement of the member b^3 to the left is continued after the jaw b' has been separated from the jaw b to its extreme limit the cam b^{16} will move out of engagement with the part b^{20} and the arm b^{23} will engage the part or sleeve e and raise the support b^2 to its elevated or initial position, where it will be supported by the pawls d d' . It will be understood, however, that the member b^3 is rocked to the left beyond its position assumed when the jaws b b' are separated to their maximum extent only when it is desired to raise the support b^2 to its elevated or initial position.

65 The movable part b^4 for determining the starting position of the vise B is here shown as journaled in the jaw b and as provided

with an outer face b^{24} for detachably engaging a longitudinally-adjustable stop f , Fig. 2, normally fixed to the frame A, and with a plurality of inner faces b^{25} , which are unequally separated from the outer face b^{24} and are movable into and out of contact with an engaging face b^{26} of the jaw b . Said movable part b^4 may be actuated by connections to the support b^2 , here illustrated as the link e' , the movable part or sleeve e , and a link b^{27} , Figs. 11, 14, 16, 17, and 21, pivoted at one end to an arm b^{28} , fixed to the movable part b^4 , and pivoted at its other end to an arm e^4 , fixed to the movable part or sleeve e . A suitable spring f' normally forces the movable part b^4 endwise for disengaging its inner faces b^{25} from the face b^{26} , and thereby obviating any liability of the movement of the part b^4 on its axis being retarded by the engagement of said faces b^{25} b^{26} . The spring f' is, however, readily compressed by the weight of the vise B when said vise is in its starting position, at which time the face b^{24} and one of the faces b^{25} are respectively in contact with the stop f and the face b^{26} . It is therefore obvious that as the part b^4 is moved on its axis it, when in operative position, separates the face b^{26} of the jaw b a greater or less distance from the stop f , thus varying the points where the needles first enter the broom B' when sewing the respective bands thereto, and thereby staggering the stitches, as will be understood by those skilled in the art. The starting position of the vise may also be varied by adjusting the stop f longitudinally. It will be understood, however, that the part b^4 may be otherwise actuated and that the stop f may be incapable of longitudinal adjustment.

The guide b^5 , Figs. 11 and 13, for the handle of the broom is secured to the jaw b by any suitable means, as a bolt b^{29} , Figs. 11 and 13, is substantially alined with the space between the broom-engaging faces of the jaws b b' , and is provided with a side b^{30} , movable laterally toward and away from the opposite portion of the guide. As best seen in Fig. 13, the lower end of the guide b^5 may be provided with a yielding section b^{31} , having an opening b^{32} of less size than the passage in the overlying portion of said guide.

The feeding mechanism for the vise B, Figs. 23 to 31, inclusive, preferably comprises a shaft g , driven and driving members h h' , a stop j , and means for holding the vise in its adjusted position. The shaft g usually supports a driving-wheel g' , loosely mounted on said shaft and connected thereto by means which may be of any suitable form, size, and construction, and is here illustrated, Figs. 28, 29, 30, and 31, as consisting of an expandible friction-band g^2 , an expanding-bolt g^3 , and a rod g^4 . Said friction-band is normally separated from an internal engaging face g^6 of the wheel g' , encircles a disk g^6 , fixed to the shaft g , and is formed with a transverse slot g^7 and with opposite portions g^8 , increasing in thickness from the slot g^7 toward the in-

termidiate portion of the band and having their inner faces provided with transverse ribs g^9 , engaged with the periphery of the disk g^6 . The expanding-bolt g^8 is arranged in a guide g^{10} in the disk g^6 and is movable endwise for causing its outer end to wedge apart the sides of the slot g^7 and engage the periphery of the band g^2 with the internal face g^5 of the wheel g' . The rod g^4 moves lengthwise in the interior of the shaft g , which is formed hollow, and said rod is provided at one end with a cam g^{11} for forcing the bolt g^8 into its operative position and is connected at its other end to a lever g^{12} , actuated by a controlling-lever G , Fig. 1. A spring g^{13} is usually provided for tending to prevent the vibration of the machine from moving the lever g^{12} out of its operative position, and a non-revoluble braking-surface g^{14} is movable with the lever g^{12} for engaging a corresponding braking-surface g^{15} , fixed to the shaft g , and facilitating the quick stoppage of the shaft g when the rod g^4 is actuated to disconnect said shaft from the driving wheel g' .

In the illustrated exemplification of my invention the driven and driving feed members h h' are connected, respectively, to the shaft g and the vise B. One of the feed members is movable into and out of engagement with the other, one of the feed members is separable from the other for varying the amount of movement transmitted thereto, one of said feed members is successively movable into engagement with the stop j during the feeding of the vise, and suitable adjusting means is provided for coöperating with said stop and controlling the length of the step-by-step movements of the vise. As here shown, the driven feed member h is connected to the vise B by means including additional feed members i i' , and the driving member h' is connected to the shaft g .

As best seen in Figs. 23 to 27, inclusive, the feed members h i are respectively movable toward and away from the shaft g and loosely movable on said shaft. The feed members h' i' are respectively fixed to and loose upon said shaft, and the stop j is adjustable in the path of the feed member i' . Said feed member h is shown as consisting of a roller carried by a pivoted lever h^2 and moved from and toward the axis of the shaft g by the feed member h' and a spring h^3 , connected to the driven feed member h by the feed member i' and a link h^4 . The feed member h is normally separated a greater or less distance from a portion of the driving feed member h' for determining the amount of movement to be given to the member h , and the extent of such separation may be regulated at will by the stop j or an adjustable part i^2 , carried by the feed member i' and movable into and out of engagement with the stop j . Said feed members i i' being both loose on the shaft g are obviously movable on substantially the same axis, and, as best

illustrated in Figs. 24 and 25, contiguous faces of these members i i' are normally engaged and frictionally connected by clutch-rollers i^3 , which are forced into their operative position by springs i^4 , carried by the member i' . The feed member i is formed with a toothed periphery, which is engaged with a feed member consisting of a toothed reciprocating bar i^5 or rack i^6 , pivoted to the jaw b , for moving the vise B forwardly step by step as the member i is intermittently advanced. The contiguous faces of the members i i' , engaged by the clutch-rollers i^3 , are so formed that as the member i is advanced by the movement of the member h the clutch-rollers i^3 move the feed member i with the member i' ; but upon the return of said member i , effected by the spring h^3 , the clutch-rollers i^3 slip along the contiguous surfaces of the feed member i without effecting retrograde movement thereof. Said clutch-rollers i^3 are generally mounted on pins or spindles provided on a rocking part or sleeve i^6 , also provided with an arm i^7 , arranged in the path of an arm i^8 , fixed to the upper end of a reciprocating bar i^9 , which is normally forced upwardly by a spring i^{10} and is connected at its lower end to a manually-operated member, as a treadle i^{11} . When the member or treadle i^{11} is depressed, the part or sleeve i^6 is actuated to force the clutch-rollers i^3 from their normal or operative position, thus permitting the vise B to be readily returned to its starting position. It will be noted that the parts h h^2 h^4 i i' i^3 i^5 all move together or as a single piece when the driven feed member h is actuated by the driving feed member h' and that the parts h h^2 h^4 i i^3 move together or as a single piece when the spring h^3 moves the driven member h into its normal position in engagement with the stop j .

The stop j determines the amount of separation of the feed members h h' , and thereby controls the length of the step-by-step movements of the vise B. The adjusting means coöperating with the stop j is here illustrated as consisting of the part i^2 , previously described, and means interposed between said stop and the vise B for varying the position of the stop. Said part i^2 may, however, be incapable of adjustment, if desired. The stop j is shown as pivoted to a part j^3 , adjustable lengthwise on one arm of a rock-shaft j' , which is held in its normal position by a spring j^2 and is provided with a second arm j^3 , normally in contact with an engaging face b^{33} upon the jaw b' . The part j^3 , to which the stop j is pivoted, is secured relatively to the corresponding arm of the rock-shaft j' by a set-screw j^6 , and said stop is movable on its pivot relatively to said part by screws j^4 . When the stop j is connected to a movable vise-jaw, as shown and described, the position of the stop and the length of the advance steps of the vise are controlled automatically by the thickness of the broom. It will be obvious, however, that the stop may be man-

ually adjusted by the screws j^4 or by moving the part j^5 lengthwise. It will also be apparent to those skilled in the art that the arm j^3 might be provided with a longitudinally-adjustable screw similar to the screws i^2 , j^4 extending through its upright sides and bearing against the face b^{33} , and that said face might be provided on the jaw b instead of the jaw b' , in which event no automatic adjustment of the stop would take place.

It will be particularly noted that I do not limit my invention to the described construction and arrangement of the means for connecting the feed member h to the vise or for coöperating with the stop j to control the length of the step-by-step movements of the vise, as these parts may obviously be constructed in many different ways.

The means for holding the vise B in its adjusted position when fed step by step may be of any desirable form, size, and construction, and is here illustrated as consisting of a part or sleeve k , mounted on the shaft g and provided with a friction face or member k' , which is forced lengthwise of the shaft g into engagement with the driven feed member i for holding the same in its adjusted position. Said part or sleeve k is generally provided with separated bearing-surfaces k^2 , engaged with the outer or upper edge of the reciprocating feed member or bar i^5 at opposite sides of a line extending through the shaft g , at right angles with the part i^5 . The surfaces k^2 hold the part i^5 in operative engagement with the feed member i and prevent the part or sleeve k from rotating on the shaft g except slightly, as the bar i^5 moves on the pivot connecting said bar to the vise B . The means for moving the part or sleeve k and its friction member k' lengthwise of the shaft g is here shown as clamping-sections k^3 , k^4 , mounted on the shaft g between the sleeve or part k and a shoulder k^5 on the shaft g and having their opposing faces provided with cam-surfaces. One clamping-section k^3 is held from rotation on the shaft by a connection k^6 to the frame A , and the other clamping-section k^4 is connected to the reciprocating rod i^9 , which holds the sections k^3 , k^4 in their operative position. When the treadle i^{11} is depressed, as previously described, for forcing the clutch-rollers i^8 from their operative position, the clamping-sections k^3 , k^4 are simultaneously forced from their operative position, thus permitting the vise B to move independently of the means for holding the same in its adjusted position.

The sewing mechanism, Figs. 3, 4, 5, 6, 9, 10, and 32 to 45, inclusive, preferably comprises a needle L for securing one end of the band to the broom, opposite needles M , M for sewing the bands to said broom, loopers N for engaging the band or thread with the needles M , M , and a band-lifter O . Said needle L is usually supported on the vise B , being here shown as provided with a hand-piece l and as movable in reverse directions in a suitable curved guide l' , having its lower

end hinged at l^2 to the jaw b' of the vise B and its upper end arranged in close proximity to the paths of the needles M , M when passing through the broom. The movement of the needle L in reverse directions in its guide l' may be limited by any desirable stops, unnecessary to describe herein. The needle L is generally connected to the support b^2 by any suitable means, here illustrated as a cam b^3 , Fig. 5, fixed to the support b^2 by the clamping-screw b^4 and provided with an inclined rib b^5 , which is engaged by one end of an arm b^6 , having its other end fixed to the guide l' . By connecting the needle L to the support b^2 by the cam b^3 and the inclined rib b^5 the movement of the support b^2 causes said needle to move relatively to the vise B and the broom B' , and the corresponding ends of the bands are secured to said article at points out of vertical alinement. In the use of the needle L it is forced to the right by hand through the broom, the thread is engaged with the hook-shaped needle end, and the needle is moved toward the left through said broom, drawing the thread there-through. After one end of the thread is secured to the broom said thread may be wrapped around the broom directly above the vise and attached to the secured end of the thread, whereupon the free unsecured end of the thread is engaged with one of the loopers N and is drawn through the broom from one side to the other side by the needles M , M .

In the preferable construction of my invention the needles M , M are normally arranged at opposite sides of the vise B and are alternately moved upwardly over said vise and through the broom in paths converging upwardly toward each other and crossing at a point substantially directly above and in close proximity to the broom-engaging face of the jaw b . Said needles M , M are here shown as pivoted at m to the outer ends of rocking arms m , m' , having their lower ends pivoted at m^2 to opposite brackets or supports m^3 upon the frame A and connected to the shaft g by suitable connections, unnecessary to describe herein. As seen in Figs. 34 and 35, the needles M , M are connected to slides m^4 , held by springs m^5 in engagement with stationary cams m^6 , which are formed with surfaces m^7 , substantially concentric with the pivots m^2 , and surfaces m^8 , extending downwardly from the surfaces m^7 . Said springs m^5 and cams m^6 cause the needles M , M to move with the outer ends of the arms m , m' in substantially curved paths during the greater part of their strokes and to then move relatively to the rocking arms m , m' during the balance of their strokes for forcing the needles during said balance of their strokes to move in substantially straight upwardly-inclined planes, passing over the vise B and extending under the band at one side of the broom B' and over the band at the opposite side of said broom. By moving the needles M , M as described it is practicable to use straight needles

on rocking arms, which is a feature of great advantage, adding to the simplicity and durability of the machine, as straight needles are much more durable than curved needles and rocking arms are a particularly simple actuating means for the needles. In the practical use of this machine the movement of the needles M M relatively to the rocking arms m' m' causes more or less wear on the pivots connecting said needles to the rocking arms and to the slides m⁴, and the advance points of the needles are caused to press upon the top edges or surfaces of the jaws b' b' of the vise with more or less force when passing beneath the bands. Suitable springs m⁶ are therefore connected to the needles M M and the rocking arms m' for taking up any looseness at the pivots for said needles, and the upper edges or surfaces of the jaws b' b' of the vise are provided with hardened removable wearing-pieces b⁸, which form needle-bearings and may be renewed when desired. The needles M M are generally provided with latches m¹⁰ and springs m¹¹ for forcing the latches into their operative position, and are here shown as consisting of a needle proper and a holder or head m¹² therefor; but as the needles M M form the subject-matter of my pending application, Serial No. 125,002, it is thought unnecessary to further describe the same. This machine is also provided with guards m¹³, which prevent contact with the needles M M during the greater part of their strokes or when moving in their curved paths and until the needles are moved relatively to the rocking arms m' m'. These guards m¹³ converge upwardly toward the vise B, in close proximity thereto, and are suitably supported on the frame A. It is sometimes desirable to vary the number of stitches made in a given distance by the needles M M, and for this reason the brackets or supports m⁸ m⁹ are adjustable relatively to the main frame A and secured together by a pivot m¹⁴, which is supported by a bracket fixed to the main frame A and is arranged beneath and substantially in vertical alignment with the broom-engaging surface of the jaw b in order that both needles may swing on a single pivot with a minimum variation of the points where the needles cross the vise. The brackets or supports m⁸ m⁹ are secured in their adjusted position by bolts m¹⁵, passed through a plurality of openings in the main frame A. The brackets or supports m⁸ may, however, be incapable of adjustment on the frame A, but when susceptible of such adjustment the connections between the rocking arms m' m' and the shaft g, which are provided with ball-and-socket joints, permit of this adjustment of said brackets or supports.

The loopers N, Figs. 32, 33, 34, 35, and 41 to 44, inclusive, are supported at opposite sides of the vise B on arms a⁵, fixed to the frame A, are of similar construction and operation, and preferably each consists of sections n n' and means for actuating said sections. As here illustrated, the sections n n' of each looper are pivoted on substantially the same pivot to a rocking crank-arm n², are provided with opposing thread-engaging surfaces n³ n⁴, and are arranged side by side, one section n being free to move with said crank-arm on the axis thereof and the other section, n', being prevented from rotation on the axis of the crank-arm n² by a pin n⁵, which is journaled in the corresponding arm a⁵ and is provided with an opening through which an extension n⁶ on the section n' is free to slide during the movement of said section. The thread-engaging face n³ of one looper-section of each looper, as the section n, consists of a part of the surface of an extension n⁷, projecting laterally into the plane in which the thread-engaging face n⁴ of the corresponding section n' is movable. Said extension n⁷ is usually composed of a part fixed to the looper-section n and provided with a roller movable relatively to said part and having the thread-engaging face n³ upon its periphery. The thread-engaging face n⁴ of the corresponding looper-section n' consists of the lower wall of an open eye provided on said section n' and having its upper wall n⁸ arranged in the path of the extension n⁷ in order to limit the movement of the looper-sections n n' relatively to each other for separating the thread-engaging surfaces n³ n⁴.

The means for actuating the looper-sections of each looper consists of the corresponding crank-arm n² and means connecting the crank-arm to the sections n n' and to the shaft g. Each crank-arm n², Fig. 43, is positively connected to the section n' of the corresponding looper by the pivot n⁹ for said section and is frictionally connected to the section n by friction-pieces n¹⁰, which are arranged on the pivot n⁹ at opposite sides of the section n and between opposing surfaces of the crank-arm n² and a shoulder on the pivot n⁹ and are drawn together by a spring n¹¹, mounted on the pivot n⁹ and adapted to be adjusted by a nut n¹² on said pivot. As the crank-arm n² is frictionally connected to the section n, said crank-arm is provided with a stop n¹³, which holds the section n in its inoperative position and is here shown, Fig. 43, as provided upon one end of a pin formed at said end with a tapered surface n¹⁴, engaged with a tapered surface n¹⁵ on the crank-arm and provided at its other end with a nut n¹⁶ for drawing the surfaces n¹⁴ n¹⁵ together and holding the stop in its adjusted position.

The means connecting each crank-arm n² to the shaft g consists of a movable bar n¹⁷, composed of separable divisions movable relatively to each other by an adjusting-screw n¹⁸ and normally secured together by clamping-screws n¹⁹, fixed to one division and movable in slots in the other division. One end of the bar n¹⁷ is provided with a toothed surface engaging a pinion n²⁰, fixed to the crank-arm n², and the other end of said bar is piv-

oted on the shaft g and provided with a roller n^{21} or other engaging part, actuated by a cam n^{22} or other driving means on said shaft.

In the operation of this machine the looper 5 N, at one side of the vise, is arranged with its opposing thread-engaging faces $n^3 n^4$ above and below the path of the needle at the same side of the vise, and as this needle returns to its normal or inoperative position it draws 10 between said surfaces the thread engaged therewith. As the needle at the opposite side of the vise is about to pass through the broom said looper is actuated to engage the thread with its surfaces $n^3 n^4$ and to move the 15 same forwardly, upwardly, and downwardly into operative engagement with said needle as it emerges from the adjacent side of the broom. The looper is then operated to disengage its faces $n^3 n^4$ from the thread in order 20 that the needle engaged therewith may be free to pull the same through the broom and through the opposite looper. By supporting and operating the looper-sections as described both sections move relatively to each 25 other when about to engage and release the thread, thus moving the faces $n^3 n^4$ in opposite directions toward and away from each other and causing the same to grasp and release the thread with great rapidity and permitting the operation of the needles with 30 maximum speed. It will be understood that after the faces $n^3 n^4$ of the looper-sections are engaged with the thread the positively-driven section n' overcomes the action of the friction means for actuating the section n and both sections $n n'$ move together. By moving the engaging faces $n^3 n^4$ in the same plane or directly opposite to each other said sections engage the thread in a particularly 35 practical and effective manner, as will be obvious to those skilled in the art.

The band-lifter O, Figs. 2 and 45, is generally movable with the vise B toward and away from the needle-path, is prevented from 45 movement with the vise after the advance end of the band-lifter has effected the desired elevation of the band, and is so constructed and arranged that said advance end when reaching the limit of its forward movement 50 is moved in a plane at substantially right angles with the plane of said forward movement in order to depress the advance end of the band-lifter beneath the needle-path. As the band-lifter is moved with the vise the rear 55 end of the band-lifter moves in a guide o , provided on the part k , previously described. The band-lifter is substantially pivoted at its front portion in a guide o^3 on the reciprocating bar i^5 , and the portion of said band-lifter 60 movable through the guide o is so formed that during the forward movement of the band-lifter the passage of said portion of the band-lifter through the guide o rocks the advance end of said band-lifter upwardly for 65 elevating the band or binder, holds said advance end in its elevated position the desired

length of time or substantially until the last stitch is sewed, and then rocks said advance end downwardly out of the needle-path. Said rear end of the band-lifter is provided with 70 a stop-shoulder o' , which engages the guide o immediately after the advance end of the band-lifter has been moved with the vise beyond the needle-path, and thus prevents said band-lifter from moving with the vise B during 75 the balance of the forward movement thereof and separates the rear edge of the broom from the advance end of the band-lifter. The advance end of the band-lifter is provided with a shoulder o^2 , which is interposed between the guide o^3 and a shoulder o^4 , provided on the reciprocating bar i^5 , and is engaged by the front end of a spring o^5 , having its rear end engaged by the shoulder o^4 . When the broom is clamped between the jaws 80 b b', the rear edge of the broom is separated from the advance end of the band-lifter, which is then arranged below its operative position. As the vise B is moved backwardly to its starting position the rear edge of the broom engages the advance end of the band-lifter and moves the same backwardly. At the commencement of the backward movement of the band-lifter its advance end is moved vertically into operative position and is subsequently depressed as the vise continues to move to its starting position. When the vise 85 B commences its forward movement, the shoulder o^4 and the spring o^5 , bearing against the shoulder o^2 , move the band-lifter forwardly with the vise until the shoulder o' engages the guide o^3 , thus preventing further movement of the band-lifter forwardly with the vise and causing the spring o^5 to become compressed between the shoulders $o^4 o^2$ as the 90 vise continues its forward movement.

The construction and operation of this broom-sewing machine will now be readily understood upon reference to the foregoing description and the accompanying drawings, 95 and it will be obvious that the construction and arrangement of its component parts may be more or less varied without departing from the spirit of this invention.

What I claim is—

1. In a broom-sewing machine, sewing mechanism, opposing jaws, one being provided with an extension projecting laterally beyond its broom-engaging face and having a pivot arranged at the outer side of the broom-engaging face of the other jaw, said first jaw being movable on said pivot, and means for forcing the movable jaw toward the other jaw, substantially as described.

2. In a broom-sewing machine, sewing mechanism, opposing jaws, one being provided with a projecting engaging part and also with an extension projecting laterally beyond its broom-engaging face and having a pivot arranged at the outer side of the broom-engaging face of the other jaw, said first jaw being movable on said pivot, and a cam having an internal

face for engaging said projecting part and forcing the movable jaw toward the other jaw, substantially as described.

3. In a broom-sewing machine, sewing mechanism, opposing jaws, one being movable relatively to the other, an engaging part provided on one jaw and adjustable relatively to said jaw, means for holding the engaging part in its adjusted position, and a cam coöperating with the engaging part for forcing the movable jaw toward the other jaw, substantially as described.

4. In a broom-sewing machine, sewing mechanism, opposing jaws, one being movable relatively to the other, an engaging part journaled in the movable jaw and provided with an eccentrically-arranged engaging face, means for holding the engaging part in its adjusted position, and means coöperating with said engaging face for actuating the movable jaw, substantially as described.

5. In a broom-sewing machine, sewing mechanism, opposing jaws, one being movable relatively to the other, a projecting engaging part provided on one jaw and adjustable relatively to said jaw, means for holding the engaging part in its adjusted position, and a cam having a recess in one of its faces for receiving the projecting engaging part, said recess having an internal face for engaging said projecting part and forcing the movable jaw toward the other jaw, substantially as described.

6. In a broom-sewing machine, sewing mechanism, opposing jaws, one being movable relatively to the other, an engaging part provided on one jaw and adjustable relatively to said jaw, means for holding the engaging part in its adjusted position, and a cam coöperating with the engaging part for forcing the movable jaw toward the other jaw, said cam having a portion thereof for coöperating with the engaging part and moving said jaw with increased power as the final compression of the broom takes place, substantially as described.

7. In a broom-sewing machine, sewing mechanism, opposing jaws, one being movable relatively to the other, a projecting engaging part provided on one jaw and adjustable relatively to said jaw, means for holding the engaging part in its adjusted position, and a cam having a recess in one of its faces for receiving the projecting engaging part, the recess having an internal face for engaging said projecting part and forcing the movable jaw toward the other jaw to compress the broom, and said internal engaging face having a portion thereof for engaging the projecting part and moving said jaw with increased power as the final compression of the broom takes place, substantially as described.

8. In a broom-sewing machine, sewing mechanism, a vise movable on an axis toward and away from the needle-path and provided with bearing-surfaces at opposite sides of its axis, and means for engaging said surfaces and re-

sisting lateral strain on the vise, substantially as described.

9. In a broom-sewing machine, sewing mechanism, a jaw movable on an axis toward and away from the needle-path and provided with bearing-surfaces at opposite sides of its axis, means for engaging said surfaces and resisting lateral strain on the jaw, and a second jaw supported by the first jaw and movable relatively thereto, substantially as described.

10. In a broom - sewing machine, sewing mechanism, an outer jaw, a second outer jaw movable laterally relatively to the first outer jaw, and a broom-support consisting of opposite jaws movable relatively to the outer jaws, means for supporting one of the jaws of the support on the first outer jaw, and means for supporting the other jaw of the support on the opposing jaw of the support and for connecting the second jaw of the support to said second outer jaw and causing said second jaw of the support to move laterally with said second outer jaw, substantially as described.

11. In a broom - sewing machine, sewing mechanism, a broom-support, a rack for the support, escapement-pawls for controlling the feed of the rack, and a manually-operated member for actuating the escapement-pawls, substantially as described.

12. In a broom - sewing machine, sewing mechanism, a broom-support, a rack for the support, means for adjusting the rack relatively to the broom-engaging face of the support, escapement-pawls for controlling the feed of the rack, and a manually - operated member for actuating the escapement-pawls, substantially as described.

13. In a broom - sewing machine, sewing mechanism, opposing jaws, one being movable relatively to the other, a broom-support movable step by step relatively to the jaws, a manually - operated member, and means connected to said member for actuating the relatively movable jaw and for controlling the step-by-step movement of the support, substantially as described.

14. In a broom - sewing machine, sewing mechanism, opposing jaws, one being movable relatively to the other, a broom-support movable step by step relatively to the jaws, escapement-pawls for controlling the step-by-step movement of the support, and a manually-operated member for actuating the relatively movable jaw and the escapement-pawls, substantially as described.

15. In a broom - sewing machine, sewing mechanism, a jaw, a second jaw supported by the first jaw and movable relatively thereto, a broom-support movable step by step relatively to the jaws, and a manually-operated member supported by one of the jaws for actuating the relatively movable jaw and for controlling the step-by-step movement of the support, substantially as described.

16. In a broom - sewing machine, sewing

the vise to an increasing resistance as said vise moves in either direction, substantially as described.

28. In a broom - sewing machine, sewing mechanism, a vise movable in opposite directions, separated stops, a connection movable with the vise in opposite directions relatively to the stops and provided with fixed shoulders, and a spring between the fixed shoulders having opposite portions alternately prevented by the stops from movement with the connection for subjecting the vise to an increasing resistance as said vise moves in either direction, substantially as described.

29. In a broom - sewing machine, sewing mechanism, a vise movable step by step, and means for feeding the vise comprising a stop adjustable for the desired length of step-by-step movements of the vise, and a feed member connected to the vise and successively movable into engagement with said stop and coöperating therewith for controlling the amount of movement of the vise, substantially as described.

30. In a broom - sewing machine, sewing mechanism, a vise movable step by step, a stop, means connected to the stop and controlled by the thickness of the broom for adjusting the stop, a feed member connected to the vise and successively movable into engagement with said stop and coöperating therewith for controlling the amount of movement of the vise, and means for actuating the feed member, substantially as described.

31. In a broom - sewing machine, sewing mechanism, a vise movable step by step, and means for feeding the vise comprising a stop, means for adjusting the stop relatively to the vise, and a feed member connected to the vise, and successively movable into engagement with said stop and coöperating therewith for controlling the amount of movement of the vise, substantially as described.

32. In a broom - sewing machine, sewing mechanism, a vise movable step by step, a stop adjustable for the desired length of step-by-step movements of the vise, a plurality of feed members, one being connected to the vise, and another being successively movable into engagement with said stop and coöperating therewith for controlling the amount of movement of the vise, and means for connecting said feed members, substantially as described.

33. In a broom - sewing machine, sewing mechanism, a vise movable step by step, a stop, means for adjusting the stop relatively to the vise, a plurality of feed members, one being connected to the vise and another being successively movable into engagement with said stop and coöperating therewith for controlling the amount of movement of the vise, and means for connecting said feed members, substantially as described.

34. In a broom - sewing machine, sewing mechanism, a vise movable step by step, driven and driving feed members, one being

successively movable into engagement with the other and one being separable from the other for varying the amount of movement transmitted thereto by said other feed member, and the driven feed member being connected to the vise, and means for varying the amount of separation of the feed members and thereby determining the length of the step-by-step movements of the vise, substantially as described.

35. In a broom - sewing machine, sewing mechanism, a vise movable step by step, driven and driving feed members, one being successively movable into engagement with the other and one being separable from the other for varying the amount of movement transmitted thereto by said other feed member, and the driven feed member being connected to the vise, means for varying the amount of separation of the feed members and thereby determining the length of the step-by-step movements of the vise, and means connected to the former means and controlled by the thickness of the broom for adjusting said former means, substantially as described.

36. In a broom - sewing machine, sewing mechanism, a vise movable step by step, a stop adjustable for the desired length of step-by-step movements of the vise, driven and driving feed members, one being successively movable into and out of engagement with the other, and one being separable from the other for varying the amount of movement transmitted thereto by said other feed member, and the driven feed member being connected to the vise, and means movable with one of the feed members, said means being successively movable into engagement with the stop and coöperating therewith for controlling the amount of movement of the vise, substantially as described.

37. In a broom - sewing machine, sewing mechanism, a vise movable step by step, driven and driving feed members, one being successively movable into engagement with the other and one being separable from the other for varying the amount of movement transmitted thereto by said other feed member, and the driven feed member being connected to the vise, a stop coöperating with one of the feed members for varying the amount of separation of said feed members and thereby determining the length of the step-by-step movements of the vise, and means for adjusting the stop relatively to the vise, substantially as described.

38. In a broom - sewing machine, sewing mechanism, a vise movable step by step, and means for feeding the vise comprising a feed member movable to and fro and connected to the vise, and means between the vise and the feed member for varying the operation of said feed member and thereby determining the length of the step-by-step movements of the vise, said feed member and means being successively detachable during the feeding of the vise, substantially as described.

39. In a broom-sewing machine, sewing mechanism, a vise movable step by step, and means for feeding the vise comprising a feed member connected to the vise and movable to and fro, and a part movable on an axis and connected to the vise and provided with a stop for varying the operation of the feed member and thereby determining the length of the step-by-step movements of the vise, said stop being detachably engaged by the feed member upon each operation thereof, substantially as described.

40. In a broom-sewing machine, sewing mechanism, a vise movable step by step, a reciprocating bar connected to the vise, a feed member for actuating the reciprocating bar, said feed member being movable on an axis, means for actuating the feed member, and a part movable on the same axis as the feed member and provided with bearing-surfaces engaged with the reciprocating bar and arranged at opposite sides of a line extending through said axis at substantially right angles with the reciprocating bar, substantially as described.

41. In a broom-sewing machine, sewing mechanism, a vise movable step by step, driven and driving feed members, one being successively movable into engagement with the other and one being separable from the other for varying the amount of movement transmitted thereto by said other feed member, and the driven feed member being connected to the vise, means for varying the amount of separation of the feed members and thereby determining the length of the step-by-step movements of the vise, and friction means for holding the vise in its adjusted position, substantially as described.

42. In a broom-sewing machine, sewing mechanism, a vise movable step by step, driven and driving feed members, one being successively movable into engagement with the other and one being separable from the other for varying the amount of movement transmitted thereto by said other feed member, and the driven feed member being connected to the vise, a stop coöperating with one of the feed members for varying the amount of separation of said feed members and thereby determining the length of the step-by-step movements of the vise, means for adjusting the stop relatively to the vise, and friction means for holding the vise in its adjusted position, substantially as described.

43. In a broom-sewing machine, sewing mechanism, a vise movable step by step, a reciprocating bar connected to the vise, a feed member for moving the bar step by step, said feed member being movable on an axis, means for actuating the feed member, and a friction member movable lengthwise of said axis for holding the feed member in its adjusted position, substantially as described.

44. In a broom-sewing machine, sewing mechanism, a vise movable step by step, a re-

ciprocating bar connected to the vise, a feed member for moving the bar step by step, said feed member being movable on an axis, means for actuating the feed member, a friction member, and means movable on the axis of the feed member for forcing the friction member lengthwise of said axis, substantially as described.

45. In a broom-sewing machine, sewing mechanism, a vise movable step by step, feed members movable on substantially the same axis, one feed member being connected to the vise, a friction member, means for connecting the feed members, means for forcing the friction member lengthwise of said axis, and a manually-operated member for forcing both of said means from operative position, substantially as described.

46. In a broom-sewing machine, sewing mechanism, a vise movable step by step, a reciprocating bar connected to the vise, a feed member movable on an axis and engaged with the reciprocating bar, means for actuating the feed member, and a part movable on the same axis as the feed member and provided with bearing-surfaces engaged with the reciprocating bar and arranged at opposite sides of a line extending through said axis at substantially right angles with the reciprocating bar, said part being movable lengthwise of said axis for holding the feed member in its adjusted position, substantially as described.

47. In a broom-sewing machine, sewing mechanism, a vise movable step by step, a reciprocating bar connected to the vise, a feed member for moving the bar step by step, said feed member being movable on an axis, a friction member, and clamping-sections, one being fixed and the other being movable on said axis for forcing the friction member lengthwise of the axis and holding the feed member in its adjusted position, substantially as described.

48. In a broom-sewing machine, a frame, a vise, and sewing mechanism comprising a rocking arm, a needle actuated by the rocking arm, and a support for the needle movable relatively to the frame and pivoted to the frame substantially directly beneath the vise, whereby the movement of the support relatively to the frame is effected with a minimum variation of the point where the needle crosses the vise, substantially as described.

49. In a broom-sewing machine, a frame, opposing jaws, one being movable relatively to the other, and sewing mechanism comprising opposite rocking arms movable toward and away from the opposing jaws, needles actuated by the rocking arms in paths intersecting substantially above the broom-engaging face of one of the jaws, and opposite supports for the needles movable relatively to the frame and pivoted to the frame substantially directly beneath said broom-engaging face, whereby the movement of the supports relatively to the frame is effected with a mini-

mum variation of the point where the needles cross said broom-engaging face, substantially as described.

50. In a broom - sewing machine, sewing mechanism comprising a rocking arm, a needle supported by the arm and movable relatively thereto, and means for moving the needle relatively to the arm during the movement of said arm, substantially as described.
51. In a broom - sewing machine, sewing mechanism comprising a rocking arm, a needle supported by the arm and movable relatively thereto, and means for moving said needle relatively to the arm during the rocking movement thereof and thereby causing the point of the needle to travel in a substantially straight upwardly - inclined line, substantially as described.
52. In a broom - sewing machine, sewing mechanism comprising a rocking arm, a needle carried by the arm and movable relatively thereto, and means for preventing movement of the needle relatively to the rocking arm during a portion of its stroke and for moving said needle relatively to the rocking arm during a second portion of its stroke and thereby causing the point of the needle to travel in a substantially straight line, substantially as described.
53. In a broom - sewing machine, sewing mechanism comprising a curved guard, a rocking arm, a needle carried by the arm and movable relatively thereto, said needle being movable in and beyond the guard, and means for preventing movement of the needle relatively to the rocking arm when the needle is moving in the guard, and for moving said needle relatively to the rocking arm during the movement thereof when the needle - point is beyond the guard and thereby causing the point of the needle to travel in a substantially straight line, substantially as described.
54. In a broom - sewing machine, sewing mechanism comprising a rocking arm, a needle pivoted to the arm, a stationary cam, and a slide movable on the arm and connected to the needle, said slide being actuated by the cam, substantially as described.
55. In a broom - sewing machine, sewing mechanism comprising a movable arm, a needle supported by the arm and movable relatively thereto, a latch movable relatively to the needle, a spring for forcing the latch into its operative position, and means for moving the needle relatively to the arm during the movement thereof, substantially as described.
56. In a broom-sewing machine, a vise, and sewing mechanism comprising a needle movable with the vise, substantially as described.
57. In a broom - sewing machine, sewing mechanism, opposing jaws, a needle, and a broom-support movable relatively to the jaws and connected to the needle for varying the position thereof relatively to the opposing jaws, substantially as described.
58. In a broom - sewing machine, sewing mechanism, opposing jaws, a needle movable

with one of the jaws, and a broom-support movable relatively to the jaws and connected to the needle for varying the position thereof, substantially as described.

59. In a broom - sewing machine, sewing mechanism, opposing jaws, a needle pivoted to one of the jaws, a broom-support movable relatively to the jaws, and a cam fixed to the support and connected to the needle for varying the position thereof relatively to the jaws, substantially as described.

60. In a broom - sewing machine, sewing mechanism, opposing jaws, a guide secured to one of the jaws and movable relatively thereto, a broom-support movable relatively to the opposing jaws and connected to the guide, and a needle movable in the guide, substantially as described.

61. In a broom - sewing machine, sewing mechanism comprising looper-sections movable in planes arranged side by side, one of the looper - sections being provided with a thread-engaging face projecting laterally into the plane in which the thread-engaging face of the other section is movable, substantially as described.

62. In a broom - sewing machine, sewing mechanism comprising looper-sections having thread-engaging faces movable in substantially the same plane, one of said faces consisting of the periphery of a roller movable relatively to the remaining portion of the corresponding looper-section, substantially as described.

63. In a broom - sewing machine, sewing mechanism comprising looper-sections movable in planes arranged side by side, one of the looper - sections being provided with a thread-engaging extension projecting laterally into the plane in which the thread-engaging face of the other section is movable, said extension being provided with a roller movable relatively to the remaining portion of the extension and having a peripheral thread-engaging face, substantially as described.

64. In a broom - sewing machine, sewing mechanism comprising looper-sections, and a power-transmitting member directly connected to one looper-section and frictionally connected to the other looper-section, substantially as described.

65. In a broom - sewing machine, sewing mechanism comprising looper-sections having thread-engaging faces, means for actuating one looper-section, and means for frictionally actuating the other looper-section relatively to the looper-section actuated by the first means and permitting said frictionally-actuated looper - section to move with the former looper-section when said thread-engaging faces are in operation, substantially as described.

66. In a broom - sewing machine, sewing mechanism comprising looper-sections having thread-engaging faces, friction means for actuating one looper-section and moving its thread-engaging face in one direction, and

means for actuating the other looper-section and moving its thread-engaging face in the opposite direction until said thread-engaging faces are in operation and for continuing to 5 actuate said other looper-section and moving both looper-sections in the same direction, substantially as described.

67. In a broom - sewing machine, sewing mechanism comprising looper-sections having thread-engaging faces, means for actuating one looper-section, friction means for actuating the other looper-section relatively to the looper-section actuated by the first means and permitting said frictionally - actuated 15 looper-section to move with the former looper-section when said thread-engaging faces are in operation, and means for varying the frictional power of said friction means, substantially as described.

68. In a broom - sewing machine, sewing mechanism comprising looper-sections having thread-engaging faces, friction means for actuating one looper-section, means for positively actuating the other looper-section, and a stop 25 for holding the frictionally-actuated looper-section in its normal position, substantially as described.

69. In a broom - sewing machine, sewing mechanism comprising looper-sections having 30 thread-engaging faces, friction means for actuating one looper-section, means for positively actuating the other looper-section, a pin having one end provided with a tapered surface and with a stop for holding the frictionally- 35 actuated looper-section in its normal position, a part having a tapered surface for engaging the former tapered surface, and means for forcing said tapered surfaces together and holding the stop in its adjusted position, sub- 40 stantially as described.

70. In a broom - sewing machine, sewing mechanism comprising looper-sections having thread-engaging faces, a shoulder on one section for limiting the amount of separation of 45 said faces, means for actuating one looper-section, and means for frictionally actuating the other looper-section relatively to the looper-section actuated by the first means and permitting said frictionally-actuated looper-section 50 to move with the former looper-section when the thread-engaging faces are in operation, substantially as described.

71. In a broom - sewing machine, sewing mechanism comprising a crank-arm movable 55 on an axis, looper - sections pivoted to the crank-arm and movable relatively thereto on an axis, said looper-sections being provided with thread-engaging faces, and means for preventing one of the looper-sections from 60 revolving with the crank-arm on the axis of said crank-arm, substantially as described.

72. In a broom - sewing machine, sewing mechanism comprising a crank-arm movable on an axis, looper-sections pivoted to the crank- 65 arm and movable relatively thereto on an axis, said looper-sections being provided with

thread-engaging faces, means for frictionally connecting one of the looper-sections to the crank-arm and causing the same to move with the crank-arm on the axis thereof until the 70 thread-engaging faces are in operation, and means for preventing the other looper-section from revolving with the crank-arm on the axis thereof and thereby preventing the looper-section frictionally connected with the crank- 75 arm from revolving on the axis of said crank-arm when the thread-engaging faces are in operation, substantially as described.

73. In a broom - sewing machine, sewing mechanism comprising a looper - section, a 80 movable bar for actuating the looper-section consisting of separable divisions, and means for moving one division relatively to the other and for securing said divisions together 85 in their adjusted position, substantially as described.

74. In a broom - sewing machine, sewing mechanism comprising a looper - section, a movable bar for actuating the looper-section consisting of separable divisions, one being 90 provided with an engaging part, driving means for engaging said part, a screw for moving the other division relatively to the division provided with an engaging part, and a 95 clamping-screw fixed to one division and movable in a slot in the other division for securing said divisions together in their adjusted position, substantially as described.

75. In a broom - sewing machine, sewing mechanism comprising a crank-arm movable 100 on an axis, looper - sections pivoted to the crank-arm and movable relatively thereto on an axis, said looper-sections being provided with thread-engaging faces, means for frictionally connecting one of the looper-sections 105 to the crank-arm and causing the same to move with the crank-arm on the axis thereof until the thread-engaging faces are in operation, means for preventing the other looper-section from revolving with the crank-arm on 110 the axis thereof and thereby preventing the looper-section frictionally connected with the crank-arm from revolving on the axis of said crank-arm when the thread-engaging faces are in operation, a movable bar for actuating 115 the crank-arm, said bar consisting of separable divisions, and means for moving one division relatively to the other and for securing said divisions together in their adjusted position, substantially as described. 120

76. In a broom - sewing machine, sewing mechanism comprising a needle, a band-lifter, a vise movable relatively to the needle-path, and means between the vise and the band-lifter for forcing the band-lifter to its operative position during the movement of the vise 125 relatively to the needle-path, substantially as described.

77. In a broom - sewing machine, sewing mechanism comprising a needle, a band-lifter, 130 a vise movable relatively to the needle-path, and means between the band-lifter and the

vise for permitting the band-lifter to move independently of the vise, for moving the band-lifter with the vise, and for forcing the band-lifter into its operative position during the 5 movement of the vise relatively to the needle-path, substantially as described.

78. In a broom - sewing machine, sewing mechanism comprising a needle, a band-lifter, a vise movable relatively to the needle-path, and means between the band-lifter and the vise for moving the band-lifter with the vise, and for permitting the vise to move independently of the band-lifter and separate the broom from the band-lifter, substantially as 15 described.

79. In a broom - sewing machine, sewing mechanism comprising a needle and a band-lifter, a vise movable toward and away from the needle-path and having opposing jaws, 20 one being movable relatively to the other for opening the vise, and means for moving the band-lifter out of its operative position inde-

pendently of the opening of the vise, substantially as described.

80. In a broom - sewing machine, sewing 25 mechanism comprising a guide, a vise, a band-lifter reciprocally movable in the guide with the vise and having a band-engaging end movable in a plane at substantially right angles with the plane of the reciprocal movement of the band-lifter, yielding means for moving the band-lifter with the vise, and means for limiting the movement of the band-lifter with the vise, substantially as described.

In testimony whereof I have hereunto 30 signed my name, in the presence of two attesting witnesses, in the city of Washington and the District of Columbia, this 5th day of April, 1902.

WILLARD C. LIPE.

Witnesses:

E. H. PARKINS,
ARTHUR E. PARSONS.
